UNITED STATES PATENT OFFICE.

OTTO THIEME, OF ST. LOUIS, MISSOURI, ASSIGNOR TO MOON-HOPKINS BILLING MACHINE COMPANY, OF ST. LOUIS, MISSOURI, A CORPORATION OF MISSOURI.

LOCKING ATTACHMENT FOR CALCULATING-MACHINES.

1,294,725.

Specification of Letters Patent. Patented Feb. 18, 1919.

Application filed March 27, 1918. Serial No. 224,957.

To all whom it may concern:

Be it known that I, OTTO THIEME, a citizen of the United States, residing at the city of St. Louis, State of Missouri, have invented a certain new and useful Improvement in Locking Attachments for Calculating-Machines, of which the following is a full, clear, and exact description, such as will enable others skilled in the art to which it appertains to make and use the same, reference being had to the accompanying drawings, forming part of this specification, in which—

Figure 1 is a vertical sectional view through the rear part of the combined adding and calculating machine to which my present locking attachment is applied.

Fig. 2 is a horizontal sectional view therethrough.

Fig. 3 is a detail side elevational view of the locking attachment.

Fig. 4 is a side elevational view of part of the means for operating the attachment.

Fig. 5 is a detail view of certain connections identified with the locking means.

Fig. 6 is a sectional view on line 6—6 of Fig. 3.

Fig. 7 is a vertical sectional view through a combined adding and typewriting machine to which my improved locking attachment is designed to be applied.

This invention relates to a new and useful improvement in locking means for calculating machines, such for instance as the Moon-Hopkins billing machine, which is a combined adding and typewriting machine, and is a division of an application filed by me May 20, 1916, Serial No. 98,853.

The object of the present invention is to arrange in connection with the tally roll printing mechanism forming the subject matter of the parent case just above referred to, certain operating connections therefor which, in addition to their other functions, provide a lock for insuring the full operation of such connections when in operative position.

I shall not in the present application go into a detailed description of the old and well known parts of the Moon-Hopkins billing machine referred to in the parent application, but will briefly state that 119 indicates a set of register wheels operated by the racks 100, which racks at their rear ends rock printing segments 561 identified with

the tally roll mechanism. 500 is the casing of the machine which incloses the adding department thereof and is removable. This casing is provided with brackets 501 (see Fig. 2), in which is mounted a shaft 502, said shaft having a groove throughout its entire length, as shown in Fig. 3. On this grooved shaft are mounted the frame pieces 503 of the laterally movable paper carriage of the tally roll printing mechanism, these frame pieces carrying at their upper ends a serrated plate 504 on the edge of which the tally roll strip may be torn, and under this plate is arranged the platen 505. 516 is the roll of paper which is supported by the frame pieces 513 depending from the frame members 503. The strip from this roll of tally paper is fed upwardly between suitable guiding and paper feeding rollers between the platen and the type carried by the type segments 561. The inking ribbon is wound on or from spools 602 and passes through suitable guides 616 located in line with the impression-making movement of the platen 505 which is incident to the rocking of the frames 503 when the shaft 502 is rocked. The printing impression on the tally roll strip follows the rearward rocking or positioning of the type-carrying segments 561 to locate appropriate printing type in the printing line and under the inking ribbon. In order to rock shaft 502 to effect this printing impression, said shaft is provided with an arm 568 whose outer end has an adjustable extension 569 coöoperating with the track plate 520 secured to the casing 500 whereby, when the frame 503 is retracted, the arm 569 serves as a stop to limit and adjust the retracted position of said frame, that is the position in which the platen 505 stands away from the printing type.

The inner end of the lever 568 is provided with an open-ended slot 568^a which lies in the path of movement of a pin 570^a on the upper end of an arm 570. This arm is provided with springs 570^b tending to hold it in a forward position with its pin 570^a out of or in advance of the slot 568^a. The lower end of lever 570 is carried by the rear end of the cam 571 loosely mounted on one of the cross shafts 86 of the machine, and whose cam slot receives a roller on a cam 266 fixed to the main operating rock shaft of the machine whereby at every operation of the machine, through the driving

connections just above described, the arm 570 will be depressed and then lifted.

The means for moving the upper end of rod 570 rearwardly so that its pin 570^a will engage with the slot 568^a, consists of a link 572 having a bifurcated rear end embracing the upper end of arm 570 and having a slot and pin connection with the side framing of the machine whereby its rear end is held 10 upwardly. The forward end of this link 572 is mounted on a rock arm 573 arranged on a sleeve 574 loosely mounted on a cross shaft 575 of the machine, the opposite or inner end of which sleeve carries a rock arm 15 connected to a bar 577. This bar has a slot and pin guiding connection at its forward end with a frame part of the machine, and is provided with an arrow head 577^a whose anticinal portions coöperate with stop 20 blocks 579 pivotally arranged in adjustable supports 578 slidingly mounted on the rack bar 39 on the paper carriage of the typewriting mechanism. In the tabulation of the paper carriage of the typewriting mechanism, when said carriage is arrested, one 25 of the blocks 579 is intended to occupy a position in front of the bar 577, irrespective of the previous direction of movement of the paper carriage, so that a stop block 579 30 will thus cause the bar 577 to be moved rearwardly and held in such rearward position while the paper carriage is so laterally adjusted. To avoid this automatic operation of the bar 577, it is obvious that the 35 blocks 579 may be removed from the rack 39 or slid to one end of the rack bar. It is usual, however, to coördinate the positions of the blocks 579 with the arrested tabulating movement of the paper carriage so that 40 at the end of each tabulating movement where it is desired to make a printing impression on the tally roll, the bar 577 will be held rearwardly. The rearward position of the bar 577 will locate the pin 570^a in the 45 slot 568^a (see Fig. 3) so that when the rock shaft 81 makes a stroke it will cause the lever 568 to be depressed, thereby rocking the frame 503 and causing the platen 505 to make a printing impression.

In order to hold the pin 570^a in the slot 568^a, I provide a guard plate 581 having a guard finger 582 located adjacent the forward end of slot 568^a. This guard plate is mounted on the shaft 502 and like the lever 568 projects through a shouldered opening C in the casing 500. A spring 583 tends to lift the forward end of guard plate 581 upwardly until it is arrested by the shoulder C' of the opening C. The normal position 55 of the parts is shown in Fig. 1. When the upper end of bar 570 is forced rearwardly so that its pin 570^a will be caused to enter the slot 568^a before any rocking of shaft 81 occurs, the parts will be in readiness to cause 60 the platen 505 to make a printing impres-

sion upon the rocking of shaft 81. This rocking of shaft 81 causes the inner end of lever 568 to be pulled upwardly and consequently the pin 570 will be located behind the guard finger 582 in such downward movement, until the pin strikes the guard plate 581, whereupon it will cause said guard plate to move with the lever 568, the guard finger preventing the pin 570 from leaving the slot 568^a during such continued 75 downward movement. As the link 570 rises, it will permit the guard plate 581 to rise until it strikes the shoulder C', whereupon said guard plate will be arrested and the end of slot 568^a opened to permit the pin 80 570^a to be moved forwardly out of said slot, if such operation is permitted by the bar 577; or if the bar 577 is held rearwardly, pin 570^a will remain in the slot 568^a in readiness to cause another printing impression 85 to be made by the platen 505 upon the next operation of the rock shaft 81.

The lever 568 carries a post 568^b which passes through a slot in the guard plate, on which post is mounted an arm 584 carrying a pin 585 for effecting the feed of the tally roll strip, but as this forms no part of my present invention, it may not be further described.

It will be observed that the printing segments of the tally roll printing mechanism are located within the casing of the machine and are thus protected from accidental injury, whereas the platen 505 for making a printing impression therefrom, together 95 with the frame and parts connected therewith, are located outside of the casing 500, the levers 568, the guard plate 581, and the paper feed operating arm 584 projecting within the casing but having detachable 100 connection with their operating parts. Hence, when the casing is removed, although the machine may be operated and the type segments 561 positioned, no printing impression can be taken therefrom.

The main operating shaft 81 which is rocked in the operation of the machine, has mounted thereon a cam 101 which vibrates a frame 105 having a restoring bar 104, which restoring bar controls levers, shown 115 in Fig. 7 and which are fully disclosed in the parent case, No. 98,853, filed by me May 20, 1916. These levers are connected to the racks 100 and when the frame 105 is moved forwardly, it permits the racks to move forwardly under the impelling action of springs 106 until arrested by setting-up devices controlled by the pin 63 which are operated by the key-positioned rods 56. When the racks 100 move forwardly and are 120 arrested in their respective positions determined by the operation of the digit keys, 3, after which operation by the bars 56, the wheels 119 or 268 are thrown into mesh with the racks and as the frame 105 is moved 125 130

rearwardly, the restoring bar 104 will operate to restore all of their racks to their normal or zero position, and in this way actuate the adding wheels 119 or 268.

5 The means for disabling the tally roll printing mechanism consists of the bar 577 which is operated by the adjustable stops on the paper carriage of the typewriting mechanism, which bar is normally held forward by means of the springs 570^b connected to the upper end of rod 570. When the bar 577 is in its forward position, as shown in Fig. 5, the pin 570^a is out of engagement with the notch in the forward end of lever 568, and consequently, the adding machine can be operated as under normal conditions, but the printing type for the tally roll attachment will not be operated. If the operator pushes back the bar 577, whose forward 10 end 577^a projects in front of the casing as shown in Fig. 7, and is available for manipulation by the operator if it is pushed back, it will cause the printing type for the tally roll attachment to become operative. 15 This can be done either manually or by adjusting into position the typewriter carriage at the forward end of the machine so that one of the blocks 578 will push back the rod 577 and hold it in its retracted position. 20 These features, however, form no part of my present invention, as they are set forth in the parent case and are claimed in divisional applications thereof which are herein referred to.

25 35 What I claim is:

1. In an apparatus of the character described, the combination of a main operating shaft, a platen operating rock shaft having a rock arm affixed thereto, said rock arm 40 having a slot in its end, a vibratable bar operated by said main shaft and having a pin in register with said slot when the parts are in their normal position, and means for moving said bar so that its carried pin will be moved into and out of engagement with said slot.

2. In an apparatus of the character de-

scribed, the combination of a main operating shaft, a platen operating rock shaft, a rock arm affixed thereto and having a slot in its end, a vibratable bar operated by said main shaft and having means for engaging said slot, and means for locking said bar to said rock arm when the parts so positioned are in other than home position.

55 3. In an apparatus of the character described, the combination of a main operating shaft, a platen operating rock shaft, a rock arm affixed thereto and having a slot in its end, a vibratable bar operated by said main shaft and provided with means to engage said slot, a laterally movable element, and means controlled by the position of said element whereby said vibratable bar is moved into and out of engagement with said 60 rock arm.

4. In an apparatus of the character described, the combination of a main operating shaft, a platen operating rock shaft, a rock arm affixed thereto and having a slot 70 in its end, a vibratable bar operated by said main shaft, a pin on said bar designed to enter said slot, controlling means for said bar to cause engagement or disengagement therebetween and said rock arm, a guard 75 member for preventing the withdrawal of said pin from said slot when the parts are in certain engaged positions, and a stop for moving said guard member to an unlocking position when the parts occupy their home 80 position.

5. In an apparatus of the character described, the combination of printing type movable to represent different numbers and their means of operation, a casing for housing said printing type, a vibratable platen mounted on the outside of said casing, and automatically detachable connections between said platen and the operating mechanism for said printing type.

85 90 In testimony whereof I hereunto affix my signature, this 21st day of March, 1918.

OTTO THIEME.
